(57) **CLAIM**

The ornamental design for a display case, as shown and described.

DESCRIPTION

FIG. 1 is a first perspective view of the display case.

FIG. 2 is a second perspective view of the display case.

FIG. 3 is a top plan view of the display case.

FIG. 4 is a bottom plan view of the display case.

FIG. 5 is a front elevational view of the display case.

FIG. 6 is a rear elevational view of the display case.

FIG. 7 is a right side elevational view of the display case; and,

FIG. 8 is a left side elevational view of the display case.

The broken lines shown in FIGS. 4 and 6 are for illustrative purposes only and form no part of the claimed design.

1 Claim, 5 Drawing Sheets

FIG. 1

FIG. 2
